KNITTING MACHINE

Fritz Lambach, Belleville, N. J., assignor to Robert Reiner, Incorporated, a corporation of New Jersey

Application October 6, 1936, Serial No. 104,244
In Germany July 15, 1936

24 Claims.

(Cl. 66—82)

The present invention relates to improvements in knitting machines, and more particularly to improvements in a heeling machine of the general description which includes two banks of needles movable as a unit for knitting the lower heel or heel flap portions of a full-fashioned stocking blank, and having yarn measuring sinkers and webholders cooperating with each of said banks of needles.

10 The machine is constructed and arranged to knit the lower heel or heel flap portions onto a full-fashioned stocking blank, in which the leg portion including the high heel sections, and the foot portion, are knitted in a continuous operation upon another machine. This stocking blank is then transferred to the heeling machine herein disclosed by topping a connecting course between the high heel sections and the foot section of the blank onto the two banks of 15 needles, the foot portion of the blank being stretched rearwardly between the sinkers and webholders while the usual take-up tension is applied to the leg portion of the blank. After the knitting of the first course, the foot is withdrawn from between the sinkers and webholders and folded forwardly to avoid interference with the continued take-up action of the machine, and the knitting of the heel flaps is then continued 20 in the usual manner as on the ordinary full-fashioned legger.

It is a principal object of the present invention to provide in a machine of this general description having two separated needle banks and their associated knitting elements operable simultaneously for knitting fabric sections into the body of a knitted fabric blank, novel and improved means for controlling the operation of the yarn feeding and knitting elements to produce knitting simultaneously and in opposite directions on the two banks of needles.

40 It is more specifically an object of the invention to provide in a heeling machine of the general type herein disclosed, novel and improved yarn carrier and slur-cock assemblies for each of the needle banks, which are arranged in the knitting of the first course for simultaneous movement in opposite directions away from each other, so that at the end of the first or connecting course, the yarn carriers will stand at the outer limits of their travel to permit the withdrawal from the rear side of the needles and folding over of the foot portion of the fabric.

It is a further object of the invention to provide a novel and more fully automatic mechanism for controlling the operation of the web-

holder elements during the initial stages of knitting the heel tabs onto a combination blank, and particularly during the operations of topping a stocking blank onto the machine, knitting the first or connecting course, and removing from 5 between the webholders and sinkers and folding forwardly of the foot portion of the fabric.

It is another object of the invention to provide an indicator device which will be of assistance to the operator in bringing the machine to 10 the precise starting position necessary for topping a new blank onto the machine, for turning the machine to the position at which the topping bar should be withdrawn, and also for bringing the machine to the correct stopping position to 15 permit the withdrawal of the foot portion of the blank from the rear side of the needles.

With these and other objects in view, a principal feature of the present invention consists in the provision of mechanism for driving the 20 yarn carrier and slur-cock assemblies associated with each bank of needles simultaneously in opposite directions toward and away from each other, so that at the end of the first knitted course, the machine may be stopped with the yarn 25 carriers at the limit of their outward or spreading movement to permit withdrawal and folding over of the foot portion of the blank without the necessity of interference with or cutting of the feeding yarn.

Another feature of the invention consists in the provision of mechanism controlled automatically as the machine is moved to starting position for tensioning the webholder elements forwardly against the needles to facilitate in the 35 topping of the stocking blank onto the machine, for returning the webholder elements to active operation during the knitting of the first course, and for again tensioning the webholder elements forwardly to permit the withdrawal of the foot 40 portion of the blank from between the sinkers and webholders.

The several features of the invention consist also in the devices, combinations and arrangement of parts hereinafter described and claimed, 45 which together with the advantages to be obtained thereby will be readily understood by one skilled in the art from the following description taken in connection with the accompanying drawings, in which Fig. 1 is a view in front elevation of the left half of the machine; Fig. 2 is a view in front elevation of the right half of the machine; Fig. 3 is a view in rear elevation of the left half of the machine as shown in Fig. 1; Fig. 4 is a view in rear elevation of the right

half of the machine as shown in Fig. 2; Fig. 5 is a top plan view of the left half of the machine; Fig. 6 is a top plan view of the right half of the machine; Fig. 7 is a sectional view taken on the line 7—7 of Fig. 1; Fig. 8 is a sectional view taken on the line 8—8 of Fig. 1; Fig. 9 is a sectional view taken on the line 9—9 of Fig. 2; Fig. 10 is a sectional view taken on the line 10—10 of Fig. 2; Fig. 11 is an end elevation looking from the right of the machine as indicated in Fig. 2; Fig. 12 is a detail view partly in section illustrating particularly the pattern lever for controlling the operation of the webholder elements; Fig. 13 is a detail view partly in section illustrating the pattern operated control mechanism for operating the stop switch of the machine; Fig. 14 is a detail view partly in section illustrating particularly the pattern control mechanism for shifting the cam shaft for narrowing; Fig. 15 is a somewhat diagrammatic view of the stocking blank topped onto a transfer bar; Fig. 16 is a detail view partly in section to illustrate the steps of the operation of topping the blank onto the machine; Fig. 17 is a fragmentary sectional view illustrating a subsequent position of certain of the parts shown in Fig. 16, at a later stage of the transfer operation; Fig. 18 is a view similar to Figs. 16 and 17 illustrating the parts in position at the completion of the transfer operation; Fig. 19 is a somewhat diagrammatic view illustrating the loop structure of the fabric course which is transferred onto the needles of the heel; Figs. 20 to 25, inclusive, are diagrammatic views illustrating the successive steps of transferring the stocking blank onto the needles of the heel, the knitting of the first course thereon, and the subsequent folding forwardly of the foot portion of the fabric, Fig. 20 representing the relative position of the needle and needle wale loops of the fabric blank subsequent to the transfer, Fig. 21 showing the relative positions after the kinking of the new fabric of the first fabric course about the needle shanks; Fig. 22 showing the relative positions of the parts subsequent to the pressing operation; Fig. 23 showing the position of the new loop as drawn through the fabric loop of the blank topped onto the needles as the needles move downwardly to the knockover position, and Figs. 24 and 25 illustrating successive steps in the operation of folding forwardly the foot portion of the fabric; Fig. 26 is a detail sectional view illustrating particularly a forward movement of the needles and webholder elements in which the foot portion of the fabric may be disconnected from its auxiliary take-up, and thereafter folded forward clear of the machine; Fig. 27 is a fragmentary view in front elevation illustrating the starting position of the carriers preparatory to the knitting of the first course; Fig. 28 is a similar view showing the position of the carriers at the outward limit of their travel at the end of the first course, and in which the foot portion of the fabric has been folded forwardly; Fig. 29 is a detail sectional view illustrating particularly the operation of the sinker slur-cock carriers during active operation of the machine; Fig. 30 is a plan view of the sinkers and a sinker actuated cam to form a knitting wave; Fig. 31 is a sectional plan view showing the dividers in their fully advanced position to re-measure the yarn; Figs. 32 to 35, inclusive, are a series of substantially identical detail sectional views illustrating the catch bar movement; Figs. 36 to 39 inclusive, show the operation of the needles

to form loops; Fig. 40 is a sectional view showing the relative position of the needle bar, sinker head and narrowing machine during the narrowing operation; Figs. 41 to 47, inclusive, are a series of detail sectional views illustrating successive relative positions of needles and transfer points during the narrowing operation; Fig. 48 illustrates the positions of the transfer loops at the completion of the narrowing operation; Fig. 49 is a somewhat diagrammatic view showing the completed heel about to be cast off from the machine; and Fig. 50 is a view of the complete stocking blank with the lower heel or heel flap sections knitted thereto.

The heel machine herein disclosed as embodying in a preferred form the several features of the present invention, is similar in many respects to flat full-fashioned knitting machines of ordinary description having spring beard needles movable as a unit with relation to a fixed press edge, cooperating yarn measuring sinkers, and webholders. The machine is provided with narrowing mechanism and pattern chain control mechanism similar in construction and mode of operation to such mechanisms employed in a full-fashioned legger for controlling the operation of the machine in knitting and shaping the heel flaps. In order to adapt applicant's machine specifically for the operation of knitting the lower heel or heel flap sections into a combination full-fashioned stocking blank, each of the two knitting sections of the machine in the preferred form, comprises two banks of needles for knitting simultaneously the two heel flap sections, space being provided between the needle banks of sufficient width to receive the intervening instep portion of the blank.

The combination full-fashioned stocking blank on which the heel operation is to be performed, as best shown in Fig. 15, preferably comprises a leg portion 60 including the high heel sections 62 and 64, and a foot portion 66 knitted integrally with the leg, the lower heel or heel flap portions being omitted, so that the entire blank may be produced in a single continuous knitting operation upon one machine. Between the high heel sections and the sole, a separating line is made by stopping the reinforcement carriers over two courses on each side of the blank. A loose course is then worked in the first reinforced course in the sole for transfer to a looper at a latter stage in the manufacture of the stocking. For the operation of transferring the combination blank described to the heel machine, the blank as shown in Fig. 15, is placed on a transfer bar 68 having two transfer point sections 70 and 72 which are engaged in the last reinforced course of the high heel sections. The stocking blank is now topped onto the heel machine so that the foot portion of the blank extends rearwardly beneath the sinkers and above the webholders, while the leg portion is tensioned forwardly by the usual take-up mechanism for the knitting of the first or connecting course of the lower heel or heel flap sections of the stocking blank. With this method of knitting the heel flaps into a connecting course of the previously knitted blank, it is necessary after the knitting of the first course, to withdraw from the machine and fold back the foot portion of the fabric to prevent interference with the operation of the knitting elements and the fabric take-up during the subsequent knitting of the heel flaps.

The several features of the present invention are directed specifically to certain improvements

in the structure and mode of operation of a heelng machine of the general type described for knitting heel flaps to a combination blank to permit of the more rapid and efficient operation of the machine particularly for topping the combination blank onto the machine, and for thereafter removing and folding forwardly the foot portion after the knitting of the first or connecting course of the heel flaps.

0 Referring specifically to the drawings, the heelng machine disclosed comprises a series of transverse frames 74 connected by the usual front rail 76 and head rail 78. The several cooperating knitting instrumentalities are driven from a main 5 cam shaft 80 extending throughout the machine length, from a motor 82 (see Figs. 1, 3 and 5) mounted on the rear of the machine. The motor 82 is connected to drive a hand wheel shaft 84 by means of a sprocket chain 86 which passes around 10 a sprocket 88 on the armature shaft 90 of the motor and sprocket 92 on the hand wheel shaft 84. The hand wheel shaft 84 is in turn connected to drive the cam shaft 80 at a relatively slow rate by means of intermeshing gears 94 and 95 carried respectively on the hand wheel shaft 84 and 15 cam shaft 80.

The present machine is provided with pattern mechanism which may be of ordinary description, comprising preferably a pattern chain 96 (see 20 Figs. 1 and 7) which passes over a pattern drum 98 and around idler rollers 100 and 102. A step-by-step movement is imparted to the pattern chain with each revolution of the main cam shaft 80 by means of a pawl lever 104 pivotally supported co-axially with the drum 98 and having mounted thereon a pawl 106 arranged for engagement with a ratchet 108 formed integrally with the drum 98. A reciprocating movement is imparted to the lever 104 and pawl 106 during 25 each revolution of the cam shaft by means of a cam actuated lever 110 (see Fig. 7) which is pivotally supported at 112 on a rearwardly extending bracket 114, and carries intermediate its length a roller 116 arranged for engagement 30 with a cam 118 on the cam shaft 80. A tension spring 120 acts to move the cam lever 110 and pawl lever 104 upwardly maintaining the roller 116 in engagement with the cam 118.

The machine disclosed in the drawings comprises two knitting sections, each having two separated banks of spring beard needles 122 which are supported on a needle bar 124 extending the length of the two sections, so that all of the needles are moved as a single unit. Associated with each knitting section is a webholder supporting bar 126 (see Figs. 2 and 9) having mounted thereon two groups of webholders 128 cooperating with the groups of needles above described. Each webholder bar 126 (see Figs. 2 and 9) is supported for vertical and forward and back swinging movements by means of two downwardly extending arms 130 pivotally mounted on forwardly extending levers 132 secured to a rock shaft 134. The present machine 55 is also provided with yarn measuring sinkers 136 and dividers 138 (see Fig. 9) which are supported for movement in a sinker bed 139 secured to the head rail 78, and are controlled by means of sinker jacks 140 and a catch bar 142 constructed and arranged to operate in the usual 60 manner for knitting on a full-fashioned cotton type machine.

The needle bar 124 is supported for vertical movements with relation to the webholder elements 128 (see Figs. 8 and 9) by means of rear-

wardly extending lever arms 144 secured to the vertical needle motion rock shaft 146, and at their rear ends pivotally secured to downwardly extending lugs 148 formed on the needle bar 126. Rocking movements are imparted to the shaft 146 by means of a downwardly extending cam lever 150 (see Fig. 8) which is provided with a cam roll 152 arranged for engagement with the usual knitting or narrowing cams on the cam shaft 80. Forward and back movements are 10 imparted to the needles through cam actuated connections from the main cam shaft which include a downwardly extending arm 156 secured to the needle bar 124 pivotally connected at its lower end to a forwardly extending link bar 158 15 which is in turn connected through a pin and slot connection to the in-and-out needle motion cam lever 160 carried on a shaft 162 and provided at its lower end with a cam roll 164 for engagement with the usual knitting and narrow- 20 ing cams on the shaft 80.

In order to permit the topping of the combination full-fashioned stocking blank above described, onto the machine, so that the foot portion thereof extends rearwardly over the webholders and beneath the sinkers, it has been found desirable to provide means for moving the webholders forwardly with the needles away from the stationary portions of the machine including the head rail 78 and sinker bed 139. In accordance with one feature of the present invention, mechanism is provided which is controlled by the pattern mechanism of the machine, and operates when the machine is brought to starting position and again after the knitting of the 35 first course, to tension the webholder elements forwardly against the needle bed so that they will move with the needles away from the machine as the needles are rocked outwardly by the operator. The forward and back movement 40 of the webholder bar 126 is preferably controlled by opposing spring tensions provided by a tension spring 166 (see Fig. 9) connected at one end to one of the supporting arms 130 for the webholder bar 126, and at its other end to a stationary hook 168 mounted on the rear of the machine, and a forwardly extending tension spring 170 connected at one end to a supporting arm 130 for the webholder bar 126, and at its forward 45 end to a vertically extending control lever 172. For the normally rearward or retracted position of the control lever 172, the spring 170 is held under a relatively low tension so that the webholder bar is maintained in a fully retracted vertical operating position as shown in Fig. 9, under 50 the influence of the spring 166. A forward movement of the control lever 172 will now operate to increase the tension exerted by the spring 170 sufficiently to overcome the tension exerted by the spring 166, so that the webholder bar 126 is 55 tensioned forwardly against the needle bar 124. 60

The control lever 172 as best shown in Figs. 2 and 9, is fixedly mounted at its lower end on a rock shaft 174 carried in supporting brackets 176 and 178 on the front rail 76. A cam lever 180 also secured to the rock shaft 174, is provided with a cam roller 182 axially movable on a roller stud 184 into operative engagement with a webholder control cam 186. The cam 186 as best shown in Fig. 9, is provided with a short 70 rise portion 188 which is arranged to engage with and move the cam roller 182, cam lever 180 and control lever 172 forwardly only for an angular position of the cam shaft 80 which corresponds exactly to the starting position of the machine.

in which the needles are at the knockover position for the insertion of the transfer bar 68 for topping the combination blank onto the needles. With the parts in this position, the webholder bar 126 is tensioned forwardly under the influence of the spring 170, and will be moved automatically away from the sinker bed 139 as the needles are rocked outwardly by the operator for the insertion of the combination blank into the machine. During the subsequent knitting of the first or connecting course of the heel flaps, the webholders are returned to active operation as the roller 182 rides off the high portion 188 of its cam 186. As the machine is then brought to a stop at the end of the first course with the needles again in the knockover position, the roller 182 and associated parts including the control lever 172, are again actuated by engagement of the roller 182 with the rise 188, to tension the webholder bar 126 forwardly against the needles, so that the webholder bar 126 will be moved forwardly as the needles are rocked outwardly by the operator to permit the removal and folding back of the foot portion of the blank prior to the knitting of a second course.

The mechanism above described for tensioning the webholders forwardly, is controlled from the pattern chain 96 through connections which comprise a cam shifting fork 190 secured to an axially movable shift rod 192 which extends along the front side of the machine, and is connected at its left hand end, as best shown in Figs. 1, 5 and 12, to a pattern lever 194 pivotally supported on a pivot pin 196. A compression spring 198 coiled about the shift rod 192 between a supporting bracket 200 for the shift rod and a collar 202, acts normally to maintain the shift rod in an extreme position to the left, in which the roller 182 is disengaged from the cam 186. The movement of the pattern chain to starting position, operates to position the first of two successive buttons under the pattern lever 194 to shift the rod 192 to the right, and thereby to bring the roller 182 into alignment with the cam 186. A second button on the chain operates to maintain the roller 182 in operative engagement with the cam 186 when the chain is racked during the knitting of the first course, so that the webholder control mechanism above described, will again be rendered operative to tension the webholders forwardly when the machine is stopped at the end of the first course of knitting to remove and fold back the foot portion of the blank. The next racking of the pattern chain which takes place during the knitting of the next succeeding course, operates to release the pattern lever 194 so that the roller 182 is again moved to inoperative position under the influence of its spring 170. The fabric supporting and tensioning devices of the present machine include an auxiliary table 206 for each knitting section (see Figs. 5 and 9) which is supported to overlie the usual work table 208 extending along the front of the machine, and has formed thereon a forwardly extending shelf 210 to receive the leg portion of the blank. Two fabric take-up straps 212 are provided with each section for tensioning the leg portion of the combination blank away from the needles, each passing forwardly over the shelf and down through a slot 214 to a take-up weight 216. There is provided with each strap a hook 220 which is arranged to be hooked into the outer portion of the fabric to provide a tension directly against the fabric wales into which the

heel flaps are to be knitted. The foot portion of the fabric is tensioned rearwardly during the knitting of the first course by means of a supplemental tensioning device comprising a take-up strap 222 secured at its upper end to the narrowing machine, and arranged to extend downwardly between the two banks of knitting needles across the face of and beneath the head rail 78 and over a guide member 224 at the rear of the machine, to a take-up weight 226. A hook 10 230 on the strap 222 provides a convenient means for connecting the take-up to the foot portion of the blank.

As best shown in Figs. 2 and 15 of the drawings, the transfer bar 68 is provided with two 15 forwardly extending ears 232 and pins 234 which are arranged for locking engagement with correspondingly slotted brackets 236 mounted on the needle bar 124 for positioning the transfer bar 68 and combination stocking blank supported 20 thereon in the machine for the initial operation of topping the blank onto the needles.

In accordance with a principal feature of the invention, the devices for feeding and sinking 25 yarn in applicant's improved heeling machine, are constructed and arranged to feed yarn simultaneously in opposite directions on the two banks of needles in each knitting section, so that the active yarn carriers feeding yarn to the two groups of needles comprising each knitting section will simultaneously finish their inward knitting strokes at the inner ends of the active groups of needles, and similarly will finish their return or outward knitting strokes at the outer ends of their travel in a fully separated position at opposite ends of the knitting section.

In the preferred construction illustrated, two knitting carriers 250 and 252 are provided for each section (see Figs. 2, 5 and 6) supported on axially movable carrier bars 254 and 256 for 40 feeding yarn simultaneously and in opposite directions to the left and right banks of needles, and also two reinforcing carriers 258 and 260 carried on bars 262 and 264 respectively for feeding yarn simultaneously and in opposite directions to the left and right banks of needles. The carrier bars 254 and 262 which carry the knitting and reinforcing carriers for the left hand needle banks for each section, are operatively connected in the usual manner to an axially movable friction rod 266 by means of frictions such as that indicated at 268 in Fig. 5, frictionally supported on the rod 266, and connected by means of an arm 270 to the carrier bar 254. The carrier bars 256 and 264 are driven from a friction rod 272 mounted in parallel relationship to the friction rod 266 by means of frictions such as that indicated at 273 in Fig. 6, on the friction rod 272 and connecting arm 274 which connects to carrier bar 256. The extent of the movement of the yarn carrier bars in each direction is controlled by means of the usual carrier stop units 275 and 276. The carrier stop unit 275 at the left end of the machine is slidably supported on a slide shaft 277 carried on a bracket 278 on 50 the head rail 78. The right hand carrier stop unit 276 is screw-threaded to and directly supported by the usual carrier stop spindle 279 which also carries on a reversely threaded portion thereof, a nut 271 which is connected to control 55 the axial movements of the left hand carrier stop unit 275. The carrier spindle 279 is given a step-by-step advancing movement to vary the carrier stroke in accordance with a predetermined pattern of operation in knitting the heel 60 75

flaps by means of the usual ratchet 280 and pawl 281 which is carried on a pawl lever 282 mounted co-axially with the spindle 279. The pawl lever 282 is connected by means of a link 283 with a cam lever 284 which is provided with an axially shiftable cam roller 285 adapted for operative engagement with a cam 286 on the cam shaft 80 of the machine. The position of the roller 285 is controlled to render the carrier stop racking device operative or inoperative by means of a roller shifting fork 287 carried on an axially movable control rod 288. In order to rack the carrier stop units outwardly to starting position, a back racking mechanism is provided which comprises a second pawl 289 and pawl lever 290 carried on the spindle 279 for engagement with a ratchet 291. The pawl lever 290 is connected by means of a rod 292 to a cam lever 293 having mounted thereon a roller 294 axially shiftable into alignment with a back racking cam 295. The back racking mechanism is controlled from the pattern chain of the machine through connections which include a roller shifting fork 296 and pattern controlled shift rod 297.

The yarn carrier assemblies including the friction rods 266 and 272, are positively driven from the cam shaft 80 of the machine through a Coulier drive, which as best shown in Fig. 4, comprises a draw arm 300 supported at its lower end on a fixed pivot 301, and at its upper end is connected by means of a latch 302 to a bracket 303 slidably supported on a bar 304. A lateral extension 305 of the bracket 303 is rigidly secured to the friction rod 266. A reciprocatory movement is imparted to the draw arm 300 carrying with it the bracket 303 and friction rod 266 by means of a Coulier cam 306 supported on a transversely extending shaft 307 and continuously engaged between two rollers 308 and 309 supported to move with the draw arm 309. The roller 309 is mounted on a depending arm 310 carried on a stationary pivot 311, and is maintained in spaced relationship from the roller 308 mounted directly on the draw arm 300 by means of a cross link 312. The Coulier cam 306 and shaft 307 are driven from the main cam shaft of the machine (see Figs. 2 and 6) by means of a bevel gear 313 on the forward end of the shaft 307 which is arranged for engagement with a bevel gear 314 sleeved on the main cam shaft 80.

The Coulier drive above described, is provided with the usual clutching and braking device which is operative by the movement of the cam shaft to narrowing position, to disconnect the gear 314 from the cam shaft 80 and to arrest the operation of the draw cam 306 and arm 300. This braking device as best shown in Figs. 4 and 6, comprises a brake band 318 which rides on a drum 320 on the shaft 307, being connected at one end to a lever 322 carried on a stationary pivot 324, and at its other end to a lever 326 carried on a pivot shaft 328. The lever 322 is provided with a gear segment which meshes with a corresponding segment formed on a tensioning lever 329 which is connected by means of a tensioning spring 321 to an upwardly extending arm of the lever 326. A roller 330 on the lever 326 rides against a flange 332 on the cam shaft 80, so that any movement of the cam shaft and associated parts to the right to narrowing position, will operate by moving the flange 332 to rotate the control lever 326 in a direction to set the brake against the tensioning strain of spring 321.

In accordance with a principal feature of the invention herein disclosed, the friction rod 266 is

connected by means of reverse driving connections to the friction rod 272, so that any movement imparted to the rod 266 will impart an equal movement to the friction rod 272, but in the opposite direction. The driving connection between the friction rods, as best shown in Figs. 1 and 5, comprises a spur gear 334 carried on a stationary pivot 336 and arranged to engage with a rack 338 secured to the left hand end of the friction rod 266, and with a rack 340 similarly secured to the friction rod 272.

Further in accordance with the present invention, two separate slur-cock assemblies are provided for advancing the sinkers in timed relation to the movement of the yarn carriers cooperating respectively with the left and right banks of needles for each knitting section of the machine. In order to provide freedom of movement for the slur-cock assemblies cooperating respectively with the left and right banks of needles, the slur-cock 350 and cam 352 operating against the sinker jacks associated with the left bank of needles, and the slur-cock 354 and cam 356 operating against the sinker jacks associated with the right bank of needles for each section, are located at different levels in the machine. The slur-cocks 350 are supported on a slur-cock bar 358 which is connected to move with the bracket 303 and friction rod 266 by means of the latch pin 360 which serves also to connect the draw arm 300 latch 302 to the bracket 303. The slur-cocks 354 are similarly supported upon a slur-cock bar 362 which is rigidly connected by means of a bracket 364 to move with the friction rod 272. Inasmuch as the slur-cocks cooperate in the usual manner with the yarn carriers associated therewith, to sink the feeding yarn against the shanks of the needles, no further description of these parts is believed necessary.

The construction and mode of operation of the mechanism for operating the catch bar 142 to advance the dividers, re-measuring the yarn against the needle shanks, and for thereafter re-tracting the sinkers and dividers, is identical with that well known in the art, but may be briefly described in connection with Figs. 8 and 9 of the drawings. Forward and back movements are transmitted to the catch bar 142 by means of upwardly extending levers 370 secured at spaced intervals to the catch bar shaft 372 and connected by links 374 to the catch bar 142. Rocking movements are imparted to the shaft 372 to advance and to retract the catch bar 142 by means of a cam lever 376 and cam roll 378 which rides against a cam 380 on the main cam shaft 80 of the machine. The catch bar vertical motion as generally indicated in Figs. 8 and 9, comprises the usual lever extension 382 secured to the catch bar, catch bar lift arm 384, bell-crank 386 pivotally supported on a shaft 388, link 390, and cam lever 392. The cam lever 392, as best shown in Fig. 9, is pivotally supported on a shaft 396, and serves to impart the usual motions to the sinker jack spring bar 398 supported on the shaft 396.

In the preferred form of the invention herein disclosed, means are provided for disconnecting the yarn carrier and slur-cock assemblies from the Coulier drive including the draw arm 300 with the feeding yarn carriers at the inner limit of their movement, after the last ravel course of the heel flaps has been knitted, so that the fabric may be quickly and efficiently pressed off by the continued rotation of the cam shaft, while leaving the carriers in the desired inside position for

the starting of a new heeling operation. The means provided for disconnecting the yarn carrier and slur-cock assemblies from the Coulier drive, comprises the latch 302 above referred to, 5 which is pivotally connected to the draw arm 300, and has formed therein a slot 404 which fits over the pin 360, and serves to provide a fixed driving relationship between the draw arm 300 and bracket 303. A tension spring 406 connected at 10 one end to the latch 302 and at its other end to the machine frame, serves normally to maintain the latch in locking engagement with the pin 360. For the convenience of the operator to disengage the latch, a hand lever 408 is secured to 15 the forward end of a rock shaft 410 (see Figs. 2 and 4) which is provided at its rear end with a lever arm 412 and roll 414 arranged upon actuation of the hand lever 408 to engage with and lift the latch when the draw arm 300 is at the limit 20 of its movement to the left as shown in Fig. 4, which corresponds to the inmost limiting position of the yarn carrier and slur-cock assemblies.

Also secured to the rock shaft 410 is a downwardly extending arm 416 which is connected to 25 a link 418 having a pin and slot connection 420 with the draw arm 300. During the subsequent rotation of the machine to press off the finished fabric, the movement of the draw arm 300 to the right from the position shown in Fig. 4, operates 2 to engage the pin with the end of the slot 420 to rock the shaft 410 and cam lever 412 in a counterclockwise direction as shown in Fig. 4, out of the path of the latch 302, so that as the rotation of the machine is continued to starting position, and the draw arm 300 is again brought to its limiting position to the left, the latch automatically drops into locking engagement with the pin 360 to re-engage the Coulier drive.

The present machine is provided with a narrowing mechanism which may be of ordinary description, and as best shown in Figs. 1, 2, 8 and 10 of the drawings, comprises the usual narrowing machine frame including a shaft 430 rigidly secured to supporting arms 432 which are pivotally mounted on shaft 304 carried on the stationary part of the machine frame. Downwardly extending brackets 436 provide support for axially movable carrier rods 438 and 440 having attached thereto groups of heel narrowing points designated at 442 and 444 and cooperating respectively with the left and right banks of needles for each knitting section. The narrowing machine frame is moved vertically by means of the usual vertically extending rod 446 connected at its upper end to the shaft 430 and at its lower end to a roller lever 448 (see Fig. 10) which is actuated by means of a narrowing cam on the main cam shaft 80 of the machine. The narrowing points are stepped inwardly to perform each successive narrowing and knitting of the heel flaps by means of the usual actuating connections including a narrowing spindle 450 supported on the narrowing machine frame and having portions thereof oppositely threaded to receive the usual narrowing spindle nuts 451 and 452 for controlling the operation respectively of the narrowing point carrier rods 438 and 440. The spindle 450 is given a step-by-step rotation during each narrowing operation to shift the 60 narrowing points inwardly by means of the usual ratchet 453 and pawl 454 (see Figs. 2 and 9) which is carried on a pawl lever 455, connected by a link 456 to a cam lever 457 which is pivotally supported on the catch bar shaft 372. At its lower end the cam lever 457 is provided with an

axially shiftable cam roll 458 arranged for engagement with a cam on the shaft 80. The movement of the cam roll 458 into and out of operative position is controlled in the usual manner by means of a shifter fork 459 and shift rod 5 460.

There is also provided with the present construction, mechanism which is rendered operative during the knitting of the ravel courses of the heel fabric, and while the narrowing machine is 10 maintained in its inoperative position, to rack the narrowing points outwardly to starting position preparatory for the starting of a new operation. This mechanism, as best shown in Figs. 1 and 8, comprises a ratchet 461 and cooperating 15 pawl 462 carried on a pawl lever 463 which is supported coaxially with the spindle 450. Secured to the sleeve hub of the pawl lever 463, is a gear segment 464 which meshes with a segmental gear 465 sleeved to turn on the supporting 20 shaft 430 of the narrowing frame. An upwardly extending arm 466 rigidly secured to the sleeve hub of the segmental gear 465, is connected by means of a link 467 to a cam lever 468 which is pivotally supported on the catch bar shaft 372, 25 and at its lower end is provided with a cam roller 469 axially shiftable into alignment with a back racking cam on the shaft 80. The roller 469 is shifted axially into alignment with its cam to start the back racking operation by means of a 30 shifting fork 476, shift rod 478, and pattern lever 480 from the pattern chain of the machine. The back racking operation is continued during the knitting of the heel flap ravel courses until the narrowing spindle has been returned exactly to 35 starting position by the locating of successive buttons on the chain which are arranged to maintain the roller 469 in alignment with the cam to produce a number of back racking movements equal to the number of narrowing operations 40 performed during the knitting of the heel flaps.

The machine, as best shown in Figs. 1, 5, 7 and 14 of the drawings, is provided with mechanism of ordinary description controlled automatically 45 from the pattern chain of the machine, for shifting the main cam shaft 80 axially to perform successive narrowing operations. This mechanism comprises the shift levers 481 pivotally supported on a stationary bracket 482, and provided 50 with cam rolls 483 adapted for engagement with opposite sides of a shift cam 484 on the cam shaft 80. The operation of the shift levers 481 is controlled by a rocker lever 485 supported on a stationary pivot 486 and having supported thereon stop screws 488 arranged for engagement with the corresponding shift lever 481. The rocker lever 485 is controlled from the pattern chain 96 of the machine by means of a pattern lever 489 (see Fig. 14) which is carried on the pivot pin 60 196 and is arranged for engagement with a lever 491 having a toggle spring connection 493 with the rocker lever 485. Inasmuch as this shift mechanism is well known in the art, no further description thereof is believed necessary.

The machine herein disclosed is provided with electrical control mechanism including a starting switch 490, a stop switch 492 and a slow speed switch 494 for driving the machine at a relatively slow rate during the successive narrowing operations. The operation of the starting switch 490, as best shown in Figs. 1 and 3, is controlled by means of the usual axially movable control rod 496 extending along the front side of the machine, which has secured thereto a rack 498 75

meshing with a pinion 500 secured to a rotatable switch rod 502. The machine stop switch is controlled automatically from the pattern mechanism of the machine, by means of an upwardly extending lever 504 (see Figs. 1 and 13) pivoted at 506 on the machine frame, and connected by means of a link 508 to a switch actuating lever 510. The lever 504 and link 508 are normally held in running position to the right against the tension of a spring 512 secured to the upper end of the lever 504 by the engagement of a projecting arm 514 of the lever 504 with a notch 516 formed in an upward extension of a pattern lever 518 supported on the pivot pin 196. With the preferred construction illustrated, a button is located on the pattern chain to engage the pattern lever to trip the lever 504 and switch 492 controlled thereby, so that the operation of the machine is automatically stopped after the knitting of the last ravel course with the yarn carriers at the limit of inward movement.

In accordance with one feature of the present invention, an indicator device is provided for indicating accurately the starting position of the machine, in which the needles are rocked outwardly and the transfer bar 68 with the combination blank topped thereon is placed in the machine. This position is extremely critical, in view of the fact that the needles must necessarily be at their extreme low position to receive the transfer bar 68, and the sinkers retracted in order to provide adequate space for placing the fabric in the machine. The indicator device referred to, as best shown in Fig. 2 of the drawings, comprises a pointer 520 secured to an adjacent cam on the cam shaft 80, and a cooperating indicator band 522 which is secured to the front rail 76, and extends upwardly over the cam shaft 80. The exact angular starting position of the main cam shaft 80 is clearly indicated by means of an arrow 524 on the band 522. This arrow also serves to indicate the subsequent stopping position of the machine in which the needles are again rocked outwardly and the foot portion of the fabric withdrawn from the machine for the knitting of the first connecting course of the heel flaps. A second arrow 526 indicates an intermediate stopping position of the machine at which the transfer bar 68 is removed after the needles have been permitted to rise sufficiently to transfer the loops onto the needle shanks during the first cycle of operations of the machine.

The operation of the machine for the knitting of the heel flaps on a combination full-fashioned leg and foot stocking blank, may be briefly described as follows:

Assuming that a combination blank has been topped onto the transfer bar 68, and is ready for positioning in the machine, the pattern chain is first turned manually through to its starting position in which a button on the chain engages beneath the pattern lever 194, shifting the rod 192, shifter fork 190, and roller 182 to the left into alignment with the webholder tensioning cam 186. The machine is now turned exactly to starting position in which the pointer 520 is opposite the arrow 524 on the indicator band 522. The needles for this position of the cam shaft, are in an extreme low position at the knockover with the sinkers still retracted. The yarn carriers 250 and 252 are located at the inner ends of their respective banks of needles as illustrated in Fig. 27, in the positions at which they were left during the press-off of a previous heelng operation. At this time the movement of the

draw arm 300 to its extreme position to the left, as shown in Fig. 4, has caused the slotted portion of the latch 302 to move into engagement with the pin 360 to operatively connect the draw arm to the yarn carrier and slur-cock assemblies. 5 The webholder elements 128 are at this time tensioned forwardly against the needle bar 124 due to the engagement of the roller with the rise 188 on the webholder tensioning cam 186.

The needles are now rocked outwardly, carrying with them webholder elements under the influence of the tensioning spring 170. The transfer bar 68 is placed in position on the needle bar 124, the foot portion of the fabric is connected to the take-up strap 222, and the leg portion is connected to the take-up straps 212 extending over the auxiliary table 206. The position of the parts is now that illustrated in Fig. 16.

The needles and the webholder elements engaging therewith, are now rocked back to their normal position, as shown in Fig. 17, and the machine cam shaft is turned manually through an angle sufficient to bring the pointer 520 opposite the arrow 526 in which the needles and transfer bar have been raised sufficiently to transfer the loops onto the needle shanks, as shown in Fig. 18, so that the transfer bar may now be removed from the machine. It is essential for the proper operation of the machine, to stop the cam shaft in substantially the correct 30 angular position in which the needles have risen sufficiently to complete the transfer of the loops from the transfer points, and at the same time not sufficiently high to cause interference between the transfer bar and parts of the narrow- 35 ing machine which is supported in close proximity to and above the needles. The position of the needles with relation to the combination stocking blank transferred thereto, substantially at the point of removal of the transfer bar, is illustrated in somewhat diagrammatic form in Fig. 20. The movement of the cam shaft 80 through only a slight angle from the original starting position has in the meantime caused the roller 182 to ride off the rise 188 of the webholder tensioning cam 186, causing the webholders again to be tensioned rearwardly against the head rail 78. 40

The machine is now turned through one complete knitting cycle to knit the first or connecting course of the heel fabric, Fig. 21 showing the 50 new course of yarn being kinked about the needle shanks, and Figs. 22 and 23 showing the successive steps of drawing the new loops through the course of fabric loops held on the needles. In the knitting of this course, the yarn carriers 250 and 55 252 will have moved outwardly beyond the edges of the fabric blanks as shown in Fig. 28.

The machine is again stopped as the pointer 520 comes opposite the arrow 524, in order to permit the foot portion of the fabric to be withdrawn from between the sinkers and webholders, and folded back out of the way. For this position of the machine, the rise 188 of the webholder tensioning cam 186 is engaged beneath the roller 182 to tension the webholder elements forwardly 65 against the needles. The needles are at the knockover, having drawn down the new course through the fabric course originally topped onto the needles.

The needles and webholders are now rocked 70 outwardly by the operator to the position shown in Fig. 26, the hook 230 of the auxiliary fabric take-up 222 is disengaged from the foot portion of the combination blank, which is now withdrawn from the beard side of the needles and 75

folded forwardly to the position shown in Fig. 28. The hooks 220 of the regular fabric take-up straps are preferably at this time engaged also into the foot fabric, so that an equal tensioning strain is secured against both sides of the fabric course through which the newly formed loops have been drawn, and thus to insure the proper take-up of the fabric during the subsequent knitting. It will be noted that the yarn carriers 250 and 252 stand at the outside limit of their movement (see Fig. 28), permitting the folding forward of the foot portion of the fabric without interference with either feeding yarn. The needles and webholders are then rocked inwardly to operating position, and the machine is started to knit the heel tabs. During the knitting of the next succeeding course as the pattern chain is again advanced in the usual manner, the pattern lever 194 rides off the second bump on the pattern chain, permitting the roller 182 to be moved out of engagement with the webholder tensioning cam 186, so that the webholders are permitted to function in a normal manner during the continued knitting of the heel flaps.

From this point the machine operates in the well known manner of the ordinary legger, to knit the heel flaps, the successive narrowings being introduced through the operation of the pattern chain and narrowing mechanism controlled thereby.

During the knitting of the final ravel courses, the back racking devices above described, are brought into operation through suitable connections controlled by buttons on the narrowing chain, to step the yarn carrier stop units 275 and 276 and the narrowing points 442, 444 outwardly to their initial starting position.

As the last ravel course is knitted, the machine is automatically stopped by the engagement of the pattern lever 518 with a stop button on the chain which operates to trip the stop lever 504 and actuate the machine stop switch 492. The operation of this switch is timed to stop the machine with the yarn carriers 250 and 252 at the limit of their inward movement, as shown in Figs. 2 and 27. In order to press off the finished fabric, the operator rotates the hand lever 408 to raise the latch 302 against the pressure of its spring 406, thus disconnecting the yarn carrier and slur-cock assemblies from the draw arm 300. The machine is then turned over, causing the fabric to be pressed off over the empty needles in the completed form shown in Fig. 50.

It will be understood that the invention is not limited to the specific embodiment shown, and that various deviations may be made therefrom without departing from the spirit and scope of the appended claims.

What is claimed is:

1. In a knitting machine having two separated needle banks and their associated knitting elements operable for knitting fabric sections into the body portion of a knitted fabric blank, the combination of a yarn carrier associated with each bank of needles, means for supporting the blank for knitting an initial course into an intermediate or connecting course of said blank, means for moving the yarn carrier associated with each of said banks of needles outwardly for the knitting of a first or connecting course on each of said banks of needles, and thereby to locate each of said active carriers at the outside selvage edge of the blank for the removal and folding over of the rearwardly extending portion of

the blank subsequent to the knitting of the first course.

2. In a knitting machine having two separated
needle banks and their associated knitting ele-
ments operable simultaneously for knitting fabric
sections into the body portion of a knitted fabric
blank, the combination of a yarn carrier asso-
ciated with each bank of needles, means for sup-
porting the blank for knitting an initial course
into an intermediate or connecting course of said
blank, and means operative during the knitting
of said initial course for moving the carriers
associated with the two needle banks simultane-
ously in opposite directions outwardly to feed
yarn. 15 10

3. In a knitting machine having two separated banks of needles movable as a unit and their associated knitting elements including yarn measuring sinkers operable for knitting fabric sections into the body portion of a knitted fabric blank, 20 the combination of means for supporting the blank for knitting an initial course into an intermediate or connecting course of said blank, a yarn carrier and slur-cock assembly associated with each of said groups of needles, and means for 25 moving each of said yarn carrier and sinker slur-cock assemblies outwardly for the knitting of a first or connecting course on each of said banks of needles, and thereby to locate each of said active carriers at the outside selvage edge of the 30 blank for the removal and folding over of the rearwardly extending portion of the blank subsequent to the knitting of the first course.

4. In a knitting machine having two separated banks of needles movable as a unit and their associated knitting elements including yarn measuring sinkers operable for knitting fabric sections into the body portion of the knitted fabric blank, the combination of a yarn carrier and sinker slur-cock assembly associated with each of said groups of needles, driving connections for the machine including a cam shaft, a draw cam, and a draw arm connected to drive said assemblies simultaneously in opposite directions, and means for disconnecting the draw arm from said assemblies with the carriers at the inside limit of movement for pressing off the finished fabric. 45

5. In a knitting machine having two separated banks of needles movable as a unit and their associated knitting elements including yarn measuring sinkers operable for knitting fabric sections into the body portion of the knitted fabric blank, the combination of a yarn carrier and sinker slur-cock assembly associated with each of said groups of needles, driving connections for the machine including a cam shaft, connections therefrom for reciprocating said assemblies simultaneously in opposite directions toward and away from each other, and means for stopping the machine at the completion of a knitting operation with the active carriers associated with each section at the inside limit of their travel. 50 55 60

6. In a knitting machine having two separated banks of needles movable as a unit and their associated knitting elements including yarn measuring sinkers operable for knitting fabric sections into the body portion of the knitted fabric blank, the combination of a yarn carrier and sinker slur-cock assembly associated with each of said groups of needles, driving connections for the machine including a cam shaft, connections therefrom for reciprocating said assemblies simultaneously in opposite directions toward and away from each other, means for stopping the machine at the completion of a 75

knitting operation with the active carriers associated with each section at the inside limit of their travel, and means for disconnecting said assemblies from their driving connections with the carriers at the inside limit of movement for pressing off the finished fabric.

5 7. In a flat knitting machine having needles movable as a unit and yarn measuring sinkers, the combination of two yarn carrier and sinker slur-cock assemblies arranged for laying and sinking yarn simultaneously on different groups of said needles, and means for reciprocating said assemblies to lay and sink yarn simultaneously in opposite directions on said groups of needles.

10 8. In a flat knitting machine having needles movable as a unit and yarn measuring sinkers, the combination of two yarn carrier and sinker slur-cock assemblies arranged for laying and sinking yarn simultaneously on different groups of needles, a friction driving rod associated with each of said assemblies, driving means including a cam and draw arm actuated thereby, a connection from said draw arm for reciprocating one of said friction rods, and a connection between 15 said friction rods for driving one from the other in the opposite direction.

20 9. In a flat knitting machine having needles movable as a unit and yarn measuring sinkers, the combination of sinker jacks for advancing the sinkers, two sinker slur-cock assemblies arranged for operation simultaneously against sinker jacks cooperating with different groups of said needles, one of said assemblies including a slur-cock cam for operation at a relatively high level against the jacks, and the other of said assemblies having a slur-cock cam arranged for operation at a relatively low level against the jacks, and means for reciprocating said assemblies to lay and sink yarn simultaneously in opposite directions on said groups of needles.

25 10. In a flat knitting machine having needles movable as a unit and yarn measuring sinkers, the combination of sinker jacks for advancing the sinkers, two yarn carrier and sinker slur-cock assemblies arranged for laying and sinking yarn simultaneously on different groups of needles, one of said assemblies including a slur-cock cam for operation at a relatively high level against the jacks, and the other of said assemblies having a slur-cock cam arranged for operation at a relatively low level against the jacks, a friction driving rod associated with each of said assemblies, and means for driving said rods simultaneously in opposite directions to produce simultaneous yarn laying and sinking in opposite directions on said groups of needles.

30 11. A flat heeling machine having, in combination, two separated groups of spring beard needles all movable as a single unit for knitting the lower heel sections of a full-fashioned stocking blank, said groups being spaced apart less than the width of instep fabric intervening between the heel flaps, yarn measuring sinkers cooperating with each of said groups of needles, a yarn carrier and sinker slur-cock assembly associated with each of said needle groups, and means for reciprocating said assemblies to lay and sink yarn simultaneously in opposite directions on said groups of needles.

35 12. A heeling machine having, in combination, two separated groups of spring beard needles all movable as a single unit for knitting the lower heel sections of a full-fashioned stocking blank, a yarn carrier and sinker slur-cock assem-

bly including a friction rod associated with each of said groups of needles, a connection between said rods whereby one is driven from the other in the opposite direction, driving connections for the machine including a draw cam and a draw arm connected to drive one of said friction rods, and means for disconnecting said draw arm from said friction rod with the yarn carriers respectively at the inner ends of their travel.

40 13. A heeling machine having, in combination, two separated groups of spring beard needles all movable as a single unit for knitting the lower heel sections of a full-fashioned stocking blank, a yarn carrier and sinker slur-cock assembly including a friction rod associated with each of said groups of needles, a connection between said rods whereby one is driven from the other in the opposite direction, driving connections for the machine including a draw cam and a draw arm connected to drive one of said friction rods, 15 means for disconnecting said draw arm from said friction rod with the yarn carriers respectively at the inner ends of their travel, and means for automatically re-connecting the draw arm to said friction rod upon the return stroke of the draw arm.

45 14. In a flat knitting machine having needles movable as a unit, and cooperating knitting elements including sinkers and webholders operable for knitting fabric sections into the body portion of a knitted fabric blank, the combination of means for supporting the blank for knitting an initial course into an intermediate or connecting course of said blank, means for rocking the needles outwardly for the insertion and subsequent folding back of that portion of the blank supported to the rear of the needles in the knitting of the initial course, means for moving the webholders outwardly with the needles, and pattern control means for rendering said 50 webholder rocking means operative.

55 15. In a flat knitting machine having needles movable as a unit, and cooperating knitting elements including sinkers and webholders operable for knitting fabric sections into the body portion of a knitted fabric blank, the combination of means for supporting the blank for knitting an initial course into an intermediate or connecting course of said blank, means for rocking the needles outwardly for the insertion and subsequent folding back of that portion of the blank supported to the rear of the needles in the knitting of the initial course, means for moving the webholders outwardly with the needles, and control devices operable to permit the said movement of the webholders only for a position of the machine with the needles at the knockover level.

60 16. In a flat knitting machine having spring beard needles movable as a unit, yarn measuring sinkers and webholder elements, the combination of pivotal supporting means for said webholder elements arranged to permit movement of the webholders forwardly with the needles to inoperative position, spring means acting normally to maintain said webholders in a rearward operating position, spring means acting when rendered operative to tension the webholder elements forwardly with the needles, a cam cooperating with said spring means to tension the webholder elements forwardly only with the needles at the knockover level, and means for operatively connecting and disconnecting said cam from the spring means controlled thereby.

65 17. In a flat knitting machine having spring

- beard needles movable as a unit, yarn measuring sinkers and webholder elements, the combination of pivotal supporting means for said webholder elements arranged to permit movement of the webholders forwardly with the needles to inoperative position, spring means acting normally to maintain said webholders in a rearward operating position, spring means acting when rendered operative to tension the webholder elements forwardly with the needles, driving connections for the machine including a main cam shaft, a cam on the cam shaft cooperating with said spring means to tension the webholder elements forwardly only for the angular starting position of said cam shaft and knitting elements controlled thereby, and pattern control means for operatively connecting and disconnecting said cam from the spring means controlled thereby.
18. In a flat knitting machine having needles movable as a unit and their associated knitting elements including yarn measuring sinkers operable for knitting fabric sections into the body portion of a knitted fabric blank, the combination of means for supporting the blank for knitting an initial course into an intermediate or connecting course of said blank, a main cam shaft and connections therefrom for actuating the needles and cooperating knitting elements, a pointer supported to turn with the cam shaft, and a stationary indicator member cooperating therewith to indicate an angular stop position of the cam shaft corresponding to the desired stop position of the knitting elements controlled thereby.
19. In a flat knitting machine having needles movable as a unit and their associated knitting elements including yarn measuring sinkers operable for knitting fabric sections into the body portion of a knitted fabric blank, the combination of means for supporting the blank for knitting an initial course into an intermediate or connecting course of said blank, a main cam shaft and connections therefrom for actuating the needles and cooperating knitting elements, a pointer supported to turn with the cam shaft, and a stationary indicator member cooperating therewith having a mark cooperating with the pointer to indicate the angular stop position of the cam shaft in which the needles are at the knockover level.
20. In a flat knitting machine having needles movable as a unit and their associated knitting elements including yarn measuring sinkers operable for knitting fabric sections into the body portion of a knitted fabric blank, the combination of means for supporting the blank for knitting an initial course into an intermediate or connecting course of said blank, a main cam shaft and connections therefrom for actuating the needles

and cooperating knitting elements, a pointer supported to turn with the cam shaft, and a stationary indicator member cooperating therewith having a mark thereon cooperating with the pointer to indicate the angular stop position of the cam shaft in which the needles have moved upwardly to the completed transfer position.

21. In a flat knitting machine having needles movable as a unit and their associated knitting elements including yarn measuring sinkers operable for knitting fabric sections into the body portion of a knitted fabric blank, the combination of means for supporting the blank for knitting an initial course into an intermediate or connecting course of said blank, a main cam shaft and connections therefrom for actuating the needles and cooperating knitting elements, a pointer supported to turn with the cam shaft, and a stationary indicator member cooperating therewith having a mark cooperating with the pointer to indicate the angular stop position of the cam shaft in which the needles are at the knockover level, and a second mark to indicate the angular position of the cam shaft at which the needles have moved upwardly to the completed transfer position.

22. In a control for the movable elements supporting the yarn carriers of a straight knitting machine, the combination comprising two sets of devices for moving said yarn carrier supporting elements, and gearing connection between said two sets of devices for their operation simultaneously in opposite directions.

23. In a driving control for a pair of yarn carrier bars of a full-fashioned hosiery knitting machine, a combination comprising: a main cam shaft, a pair of friction rods, a friction box on each friction rod having a driving connection with a carrier bar, mechanism for driving one of said friction rods from said main cam shaft, and means having an operative connection with one of said friction rods and an operative connection with the other of said friction rods for driving one of said friction rods in an opposite direction to the travel of the other friction rod, said means consisting of a rack connected to each friction rod and a gear operatively engaging both racks.

24. In a control for the movable elements supporting the yarn carriers of a straight knitting machine, the combination comprising: two sets of devices, each including a friction mechanism for moving said yarn carrier supporting elements, and a rack and gear connection between said two sets of devices for the operation of the friction mechanisms simultaneously in opposite directions.

FRITZ LAMBACH.
